UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO, CANADA.

MANIFOLDING SALES-BOOK.

1,185,284.

Specification of Letters Patent. Patented May 30, 1916.

Application filed January 28, 1913. Serial No. 743,035.

To all whom it may concern:

Be it known that I, EDWARD K. BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

My present invention relates to sales books and especially manifolding sales books of the triplicate type.

It has for its object to provide a convenient book with means for attaching the pad of triplicate leaves thereto in a simple manner so that new pads may be substituted for old with facility.

To this end it comprises the usual support and an auxiliary support for the main pad, a pad retaining means being secured to the main support; the pad retaining means is composed of plates of thin resilient metal having upturned flanges so as to form a receptacle beneath the auxiliary support in which the used leaves of the triplicate book may be conveniently disposed and in which they will be protected when filed in this way.

In the accompanying drawings, wherein is shown one of various possible embodiments of this invention,—Figure 1 is a perspective view of the complete book in normal operative position, with certain parts folded over or torn away for the sake of clearness; Fig. 2 is a side elevation of the flange 22; Fig. 3 is a central transverse section of the complete book showing the pad-attaching device; Fig. 4 is an enlarged plan view of a portion of the holder.

Similar reference characters refer to similar parts throughout the different views of the drawings.

Referring now in detail to the drawings, and more particularly to Fig. 1, there is shown a holder comprising top and bottom cover portions 1 and 2, respectively, connected by means of a flexible hinge 3 along adjacent edges. To the opposite side edge of the bottom cover 2 is secured, by means of a flexible connection, such as a hinge 4, an auxiliary support 5, upon which is mounted a pad 6 which, in the present embodiment, comprises a continuously folded

web forming a plurality of sets of original and duplicate leaves. At one end of the 55 holder is provided a binder or clamping device 7 engaging the ends of the sets. The binder is resiliently connected with the back- 60 ing by means of spring arms 8. This clamp- 65 ing device carries a double-faced carbon sheet 10, and by means of the spring-arms 8 accommodates itself to the pad as its thick- 70 ness diminishes, due to the removal of sets of leaves, and thus temporarily binds one end of the pad to prevent streaming. At the 75 opposite end of the pad is another clamp 11 similarly connected with the holder by arms 8, to hold the opposite ends of the sets of leaves in proper position.

Secured to the bottom cover 2 of the 80 holder is a pad-retaining device for receiv- 85 ing and holding the back or cover of a trip- 90 licate pad 12, the tissue leaves of which are to be successively interposed as at 13 be- 95 tween the upper surface of the carbon sheet 75 10 and the under surface of the top original leaf 14 when the book is in operative posi- 100 tion, as shown in Fig. 1. In this manner an impression recorded upon the upper sur- 105 face of the original sheet 14 is reproduced upon the upper surface of the under dupli- 110 cate leaf 15 by means of the under surface of the carbon sheet 10, as well as the under surface of the tissue leaf, due to the coating upon the upper surface of the carbon sheet 10.

The retaining device for holding the trip- 115 licate pads in proper place shown in Figs. 2, 3 and 4, is preferably stamped from sheet metal of slight resiliency and then folded 120 back upon itself along one side edge 16 to provide two plates 17 and 18, the lower plate 17 being secured directly to the bottom cover by means of rivets or other suit- 125 able fastening devices 20, whereby they rest 130 in planes substantially parallel thereto. A slight space is provided between the upper and lower thicknesses in order to receive the back, or Manila paper cover 21, of the triplicate pad. The free edges of the plates 100 forming said retaining device are turned 135 upward to provide a pair of oppositely dis- 140 posed flanges 22 and 23 respectively, also spaced apart to permit that portion of the cover to the pad near the binding to rest be- 145 tween them. In constructing the pad the

back or cover is preferably creased along a line 24 substantially parallel to and about one-half an inch from the stitched or bound connection between the leaves and the cover, 5 in order that the cover may be folded conveniently to accommodate itself to the angle between the body portion of the retaining device and the upturned flanges. The flanges 22 and 23 of the retaining device 10 are preferably cut along irregular lines, as shown in Fig. 2, in order to provide several points of support for the cover of the pad and limit the lateral movement or swinging thereof. This irregular cutting also permits 15 the ready removal of any foreign substance that may become lodged between these supports. The flange 22 of the under plate which, it will be noted, is higher than 23, is also provided with an inwardly bent lug 20 25 (Fig. 4) to engage the top of the flange 23 of the upper plate, to prevent a separation of the two plates when the cover is pushed between them as shown in Fig. 3. To insure against bending or distortion of 25 the upper plate 18 of the retaining device, lines of corrugations 26, as shown in Figs. 3 and 4, are preferably provided extending along two or more sides.

As shown in Fig. 3, it will be noted that 30 the retaining device is turned up at its closed side 16 to protect the filed tissue leaves 19 from contact with the under side of the backing, forming with the flanges and abutment a receptacle in which the 35 leaves 12 may be disposed to be filed, thereby preventing these leaves from becoming curled or torn along the edge, due to the rubbing between the backing 5 and the cover 2 because of the flexible connection 4. The 40 plates of the retaining device are also provided with a cut-away portion 28 in the central part in order to save metal and reduce weight, as well as to permit the removal of any foreign substance or object 45 which may lodge between the upper and lower plates.

A convenient method of operating a book of this character is substantially as follows:—The filler or pad 6 of original and 50 duplicate leaves is mounted upon the auxiliary support 5 by raising the clamps 7 and 11 and inserting the pad under them, whereupon they press down upon the end edges of the pad. The triplicate pad of 55 tissue leaves is inserted at one end of the retaining device, after folding the cover 21 along the creased line 24 above mentioned and slipping the cover in endwise from the top between the upper and lower plates 60 until the lower edge of the cover 21 engages the bent-over lug 25. The free end of the web is then removed from under the retaining member 7 at the top of the book, and one of the tissue leaves 13 of the triplicate 65 pad is laid over the carbon sheet 10; the

original leaf 14 is then folded back into operative position, as shown in Fig. 1. The book is then ready to receive the inscription to be recorded. After completing the recording of the transaction the support carrying the pad 6 is swung about its flexible connection 4 to withdraw the tissue leaf 13 from its position between the original and duplicate leaves, whence it falls upon the upper surface of the retaining device. 70 In this manner a bound set of copies of all entries may be conveniently kept on file, as shown in Fig. 3. The support 5 is then swung back to hold the triplicate leaves in filed position and the upper or free end of the web is grasped by the fingers of the operator to pull the set of leaves out from beneath the clamp 11. A continued movement also separates the top edge of the next original leaf from the upper clamp 7, 85 after which the original and duplicate leaves are separated from the pad, as well as from each other, along their lines of fold, and disposed of as may be desired. The next tissue leaf is then laid over the carbon sheet, 90 which automatically falls back into operative position, and the next original leaf is turned back over it.

It is thus seen that this invention provides a simple and practical form of triplicate 95 book adapted to accomplish, among others, all of the objects and advantages above set forth.

As many changes could be made in the above construction and many apparently 100 widely different embodiments of this invention could be made without departing from the scope thereof, it is intended that all matter contained in the above description or shown in the accompanying drawings shall 105 be interpreted as illustrative and not in a limiting sense.

Having described my invention, what I claim as new and desire to secure by Letters Patent is:

1. In a manifolding sales book, in combination, a main support, an auxiliary support and a pad thereon; a pad retaining device secured to the main support and comprising two resilient metal plates having flanges turned up at the sides and spaced apart at the edge next to the bound part of the pad, a second pad, a cover therefor disposed between the plates and the flanges at one side thereof; the upper plate and flange forming a receptacle for the leaves of the second pad, located between the supports. 115

2. In a manifolding sales book, in combination, a pad, an auxiliary support carrying the pad, a main support, a pad retaining device thereon comprising upper and lower flat plates one of which is attached to the support, the plates being parallel to the support and having their sides turned up to form flanges and also being turned up at 120 125 130

the side opposite the flanges to form an abutment, a second pad, and a cover therefor between the plates; the upper plate and the flanges and the abutment forming a receptacle in which the leaves of the second pad may be disposed when desired.

3. In a manifolding sales book, in combination, a pad, an auxiliary support carrying the pad, a main support, a pad-retaining device thereon comprising upper and lower flat plates integrally attached at one side and one of which is attached to the support and having their edges turned up to form flanges, and also turned up where they are joined together opposite the flanges to form an abutment, a second pad and a cover therefor located between the plates; the upper plate, flanges and abutment forming a receptacle in which the leaves of the second pad may be disposed when desired.

4. In a manifolding sales book, in combination, a cover, a pad support hinged thereto, a series of leaves removably connected thereto on lines parallel to said hinge, a pad on said support comprising a second series of superposed leaves, and means extending transversely of said hinge adapted to connect said pad to said support, said means comprising a pair of plates secured to said cover, lying between said cover and said support when said book is in normal operative position, and spaced apart so as to receive one of said first mentioned series of leaves therebetween.

5. In a manifolding sales book, in combination, a cover, a pad support hinged thereto, a series of leaves connected thereto on lines parallel to said hinge, a pad comprising a second series of superposed leaves on said support, and means extending transversely of said hinge connecting said pad to said support, said means comprising a pair of plates secured to said cover, lying between said cover and said support when said book is in normal operative position, and spaced apart so as to receive one of said first mentioned series of leaves therebetween, said plates having flanges transverse to the plane of said cover, said flanges being spaced apart.

6. In a manifolding sales book, in combination, a cover, a pad support hinged thereto, a series of leaves connected thereto on lines parallel to said hinge, a pad comprising a second series of superposed leaves on said support, and means extending transversely of said hinge connecting said pad to said support, said means comprising a pair of plates secured to said cover, lying between said cover and said support when said book is in normal operative position, and spaced apart so as to receive one of said first mentioned series of leaves therebetween, said plates having flanges transversely to the plane of said cover, said flanges being

spaced apart, one of said flanges having a lug engaging the other flange.

7. In a manifolding sales book, in combination, a cover, a pad support hinged thereto, a series of leaves connected thereto on lines parallel to said hinge, a pad comprising a second series of superposed leaves on said support, and means extending transversely of said hinge connecting said pad to said support, said means comprising a pair of plates secured to said cover, lying between said cover and said support when said book is in normal operative position, and spaced apart so as to receive one of said first mentioned series of leaves therebetween, said plates having flanges transverse to the plane of said cover, said flanges being spaced apart, and their outer edges being irregular in outline.

8. In a manifolding sales book, in combination, a holder, a support hinged along one side edge, coöperating pads mounted respectively on said holder and support, and a pad retaining device secured to the upper surface of the holder comprising a pair of flat plates connected together along one side and having their opposite sides upturned and spaced apart to engage the cover of the pad loosely therebetween and prevent a lateral withdrawal of said pad.

9. In a manifolding sales book, in combination, a holder, a support hinged along one side edge, coöperating pads mounted respectively on said holder and support, and a pad retaining device secured to one of said parts comprising a pair of flat plates connected along one side and having their opposite sides upturned and spaced apart to engage the cover of the pad and prevent a lateral movement thereof, said retaining device being open at the end to permit endwise insertion or removal of said pad.

10. In a manifolding sales book, in combination, a holder, a support connected along one edge, pads mounted respectively on said holder and support, the leaves of which are adapted to coöperate whereby multiplicate copies may be produced, a retaining device for one of said pads secured to the upper surface of the holder comprising a pair of flat plates connected together along one side and having their opposite edges upturned and spaced apart to engage the cover of the pad and prevent a lateral withdrawal thereof, said retaining device being open at one end to permit the insertion of the cover of the pad, and a stop at the other end of the device to arrest the movement of the pad when being inserted.

11. In a manifolding sales book, in combination, a holder comprising a bottom cover, a support hinged to said cover, a pad comprising a plurality of sets of original and duplicate leaves mounted upon said support, a coöperating pad of tissue leaves

1
mounted upon said support, a cover therefor
and retaining means upon said support for
engaging the cover of said last-mentioned
5 pad comprising a pair of spaced metallic
plates lying parallel to the plane of said sup-
port between which the cover of said pad
is clamped, said plates being connected by
an upturned flange along one side protecting

the tissue leaves when resting on one of the
plates.

10

In testimony whereof I affix my signature,
in the presence of two witnesses.

EDWARD KIRBY BOTTLE.
